UNITED STATES PATENT OFFICE.

HERMAN JANSEN, OF SCHIEDAM, NETHERLANDS.

STATIONERY.

1,275,934.

Specification of Letters Patent. Patented Aug. 13, 1918.

Application filed April 18, 1918. Serial No. 229,457.

To all whom it may concern:

Be it known that I, HERMAN JANSEN, distiller, residing at Schiedam, the Netherlands, have invented certain new and useful Improvements in Stationery, of which the following is a specification.

My invention relates to stationery and particularly to letter sheets the object of my invention being to provide a letter sheet 10 having on one face thereof, a correspondence field and an address field, said sheet being provided at one edge with a flap by which the sheet may be held when properly folded to inclose the correspondence field and expose the address field.

In the accompanying drawings,

Figure 1 is a face view of a correspondence sheet in which my invention is embodied; and

20 Figs. 2, 3, 4 and 5 are similar views showing the successive folds of the sheet to form the closed and sealed letter illustrated in Fig. 5.

The invention relates to that type of self-contained letter sheet which embodies not only a correspondence field, but also an address field and marginal flap means for holding the sheet folded. The special object of the invention is to provide a novel sheet of 25 this character in which the correspondence and address fields are not only on the same side of the sheet (to facilitate the making of copies by carbon or press) but also so related to each other and to the sheet as a 30 whole that the latter may be folded to present the address field on the outside of the folded sheet, but to conceal the correspondence field within the folded sheet, while the 35 whole may be maintained in folded position 40 by a single flap at one end of the sheet.

Referring to the drawings, the sheet 6 is here indicated as divided longitudinally into thirds, two thirds being occupied by the correspondence field which extends the full 45 width of the sheet, and the remaining third having, in only its central portion, an address field 8, both fields being on the same face of the sheet. Outside the address field but within the same third of the sheet and 50 on the same face, are placed the name and address of the writer. The precise location of this "return address" on this portion of the sheet is not material, but I have shown

it adjacent the bottom edge 9 of the sheet, in the position preferred by the postal authorities of my country. At the opposite end of the sheet a holding flap 10 is provided, the side margins of which are substantially aligned with the sides of the address field 8. This flap is preferably not gummed, since it 55 may be desired to insert the letter in a copy press, if the copy is not made by carbon.

After the letter and address have been written on the sheet within their respective fields—and this may be done on a type-writer at a single insertion of the sheet, since both letter and address are on the same face of the sheet—the lower third of the sheet is folded against the back of the sheet as indicated in Fig. 2. The side margins of the 60 sheet are then folded forward over the correspondence field, these side folds having a transverse extent corresponding to the distance between the margins of the sheet and the address field 8 at one end and the margin of the sheet and the sides of the flap 10 at the other end. It will be noted that inasmuch as this fold occurs after the lower third of the sheet carrying the address field 65 has been folded upward against the back of the sheet, this address field portion is held snugly against the back of the lower portion of the correspondence field. The third operation consists in folding the correspondence field in half, face to face, Fig. 3. This 70 brings the upper end of the sheet adjacent the line of the first fold and the remaining operation is merely to fold the flap over this bend and down on the address field portion of the sheet, where it is secured by any suitable means—such as by pasting it in place 75 or by applying the postage stamps as shown in Fig. 5.

It will thus be seen that the missive is 80 folded zigzag, the first fold being held in place by the inturned margins which are folded over before the second zigzag fold is made, while the flap 10 secures the whole.

As above stated, all written or printed matter is confined to one face of the sheet, 85 which is an economy, as well as an advantage from the standpoint of making copies. Since the flap 10 need not be gummed, press copies may be made without inconvenience. There is also the obvious economy of time 90 and labor in that no separate envelop is used.

I claim as my invention:

A letter sheet comprising at one end a correspondence field extending substantially the full width of the sheet, and an address field on the same face at the opposite end of the sheet but of materially less width than the sheet, said sheet being longitudinally folded zigzag to leave exposed only that portion of said face which contains the address field and having the side margins of the

correspondence field folded upon the mid portion of the correspondence field after the first zigzag fold is made, together with an end flap at the end of the correspondence field adapted to be folded on and secured to the exposed face of the address field, substantially as described.

In testimony whereof I affix my signature.

HERMAN JANSEN.

Copies of this patent may be obtained for five cents each, by addressing the "Commissioner of Patents, Washington, D. C."
